US00D964137S

(12) **United States Design Patent** (10) Patent No.: **US D964,137 S**
Takashima (45) Date of Patent: **** Sep. 20, 2022**

(54) **CUTTER KNIFE**(71) Applicant: **OLFA CORPORATION**, Osaka (JP)

JP D1244247 S 6/2005

JP D1574094 S 4/2017

JP D1619439 S 12/2018

(72) Inventor: **Yosuke Takashima**, Osaka (JP)

Primary Examiner — Darlington Ly

(73) Assignee: **Olfa Corporation**, Osaka (JP)

(74) Attorney, Agent, or Firm — Crowell & Moring LLP

(**) Term: **15 Years**(57) **CLAIM**(21) Appl. No.: **35/511,453**

The ornamental design for a cutter knife, as shown and described.

(22) Filed: **Feb. 10, 2021****DESCRIPTION**(80) **Hague Agreement Data**Int. Filing Date: **Feb. 10, 2021**

1. Cutter knife

Int. Reg. No.: **DM/212749**

2. Cutter knife

Int. Reg. Date: **Feb. 10, 2021**

1.1 is a top, front, and right side perspective view of a cutter knife embodying my new design in accordance with a first embodiment;

Int. Reg. Pub. Date: **Feb. 26, 2021**

1.2 is a bottom, front, and right side perspective view thereof;

(30) **Foreign Application Priority Data**

Aug. 26, 2020 (JP) ..... 2020-017875 D

1.3 is a right side elevation view thereof;

Aug. 26, 2020 (JP) ..... 2020-017876 D

1.4 is a top plan view thereof;

Aug. 26, 2020 (JP) ..... 2020-017877 D

1.5 is a bottom plan view thereof;

(51) LOC (13) Cl. **08-03**

1.6 is a front elevation view thereof;

(52) U.S. Cl.

1.7 is a rear elevation view thereof; and

USPC **D8/98**

1.8 is an exploded top, front, and right side perspective view thereof with the blade separated from the handle.

(58) **Field of Classification Search**

2.1 is a top, front, and right side perspective view of a cutter knife embodying my new design in accordance with a second embodiment;

USPC D8/16, 70, 94, 98, 99, 101, 102, 105,

2.2 is a bottom, front, and left side perspective view thereof;

D8/107; D22/118

2.3 is a right side elevation view thereof;

(Continued)

2.4 is a left side elevation view thereof;

(56) **References Cited**

2.5 is a top plan view thereof;

U.S. PATENT DOCUMENTS

2.6 is a bottom plan view thereof;

5,269,063 A * 12/1993 Okada B26B 5/002

2.7 is a front elevation view thereof;

30/162

2.8 is a rear elevation view thereof; and

5,502,896 A * 4/1996 Chen B26B 5/002

2.9 is an exploded top, front, and right side perspective view thereof with the blade separated from the handle.

30/162
